UNITED STATES PATENT OFFICE.

JOSEPH F. JOY, OF BELLE VERNON, PENNSYLVANIA, ASSIGNOR TO THE JEFFREY MANUFACTURING COMPANY, OF COLUMBUS, OHIO, A CORPORATION OF OHIO.

PROTECTIVE DEVICE.

Application filed November 21, 1916, Serial No. 132,709. Renewed June 13, 1922. Serial No. 568,078.

To all whom it may concern:

Be it known that I, JOSEPH F. JOY, a citizen of the United States, residing at Belle Vernon, in the county of Fayette and the 5 State of Pennsylvania, have invented certain new and useful Improvements in Protective Devices, of which the following is a specification, reference being had therein to the accompanying drawing.

10 The present invention relates to certain new and useful improvements in protective devices and particularly that class of protective devices which are adapted to prevent certain abuses in the operation of electric 15 locomotives.

It is common knowledge that when power is applied to the driving wheels of a locomotive sufficient to cause their rotation faster than the locomotive advances along the rails, 20 the adhesion of the wheels to the rails is materially decreased and the tractive effort of the locomotive proportionately reduced. In their attempts to avail themselves of the greatest possible tractive effort while pulling 25 heavy trains up grades motor men habitually increase the power of the motors until the wheel slips. To reestablish the grip of the wheels upon the rails the power should be sufficiently curtailed to reduce the peripheral 30 speed of the driving wheels to the rate of advance along the rails. In operating certain classes of electric locomotives the practice has developed of retarding the rotation of the driving wheels, when slipping, 35 by the pressure of the brake shoes upon the treads of the wheels. This practice results in the extravagant consumption of power, the undue straining of the motors and transmission gearing, and the wasteful 40 wearing of the wheel tires and brake shoes.

It is the especial object of this invention to provide, in locomotives of the class described, devices which shall automatically prevent the energizing of the motors when 45 the wheel brakes are applied.

The devices by which I attain this object are fully set forth in the following specification and illustrated in the accompanying drawing of which—

50 Fig. 1 is a side elevation of a locomotive of the class to which my protective device is applicable.

Fig. 2 is a plan view of the locomotive shown in Fig. 1 the cover plates being broken away to reveal the brake mechanism and the 55 application of my protective device thereto.

Fig. 3 is a diagrammatic figure showing the relation of my protective device to the electric circuits of the locomotive.

Like numerals refer to similar parts in 60 the several figures.

In the drawing is illustrated a locomotive adapted to use in coal mines, and the like, having a frame composed of the side plates 1 and end plates 2 which are securely joined by connecting angles 3 and bolts 4. To the end frames 2 are attached the bumpers 5 which are provided with draw eyes 6 adapted to receive the coupling pins by which the locomotive is connected with its load. The 70 side plates 1 are mounted, in the usual manner, upon axles 7 to which are fixed the driving wheels 8 adapted to travel along the rails 9 of the mine track. Positioned between the side plates 1 are motors 10 upon the frames 75 of which are formed journal bearings 11 which engage the axles 7 to support the motors. Suitable spur gears, not shown in the drawing, connect the armatures of the motors with the axles to drive them. A trolley 80 pole 12 is mounted upon the frame of the locomotive and adapted to contact with the trolley wire 13 to supply electric current to the motors. A controller 14 is connected between the trolley 12 and the motors 10 to 85 control the operation of the motors in the manner common to electrically propelled vehicles. Suspended from the side plates 1 by the lever bars 15 and 16 are brake shoes 17 adapted to contact with the driving 90 wheels in the manner common to wheel brakes. The lever bars 15 have extensions 18 by which they are connected through the links 19 with the levers 20, fulcrumed on the extensions 21 of the levers 16. The upper 95 end of the levers 20 are connected through the links 22 with the equalizing bar 23 extending across the locomotive and slidably in the slots 24 of the side plates 1. Pivotedly connected at the center of the equalizing bar 100 23 is a screw nut 25 in which is threaded a screw shaft 26 which extends longitudinally of the locomotive and is rotatable in an aperture of the cross bar 27 rigidly secured to the

side plates 1 of locomotive frame. Attached to the shaft 26, outside the cross bar 27 is a hand wheel 28 by which the shaft may be rotated to cause its movement in the nut 25 relative to the equalizing bar 23. By the rotation of the hand wheel 28 in one direction the brake shoes 17 will be forced into contact with the wheels 8 to retard their rotation, and by the rotation of the hand wheel 28 in the other direction the brake shoes will be moved away from the wheels. Formed on the hub of the hand wheel 28 is a flange 29 which is adapted to contact with the contact spring 30 mounted upon an insulating base 31 supported on the cross bar 27. This spring 30 is connected by a conductor 32 with the actuating coil 33 of a contact switch 34 adapted, when current is flowing through the coil 33, to connect the conductor 35 from the trolley 12 with the conductor 36 to the controller 14. By this arrangement of parts, current will flow from the trolley 12 through the conductor 32, coil 33 and contact spring 30 to ground through the locomotive frame. When the above described circuit is closed the coil 33 will be energized to close the switch 34 allowing current to flow from the trolley 12 through the switch 34 and controller 14 to energize the motors of the locomotive. A compression spring 37 is interposed between the hand wheel 28 and the cross bar 27 which will be compressed whenever pressure is applied to the brake shoes 17 allowing the flange 29 to move away from the spring 30, interrupting the circuit through the coil 33, causing the switch 34 to open, interrupting the motor circuit and effectually preventing the actuation of the motors while the brakes are set. When the pressure on the brake shoes is released the spring 37 pushes the flange 29 rearwardly, restoring the contact with the spring 30 to reclose the switch 34. By the combination of elements above described the application of the brakes automatically cut off the current from the motors of the locomotive, effectually preventing the straining of the motors and transmission gearing, the extravagant consumption of current and the wasteful wearing of the wheel tires and brake shoes.

What I claim is—

1. In a protective device of the class described, the combination with a locomotive having driving wheels, of electric motors to drive the wheels, brake shoes adjacent the wheels, means to press the brake shoes against the wheels comprising a screw shaft adapted to limited longitudinal movement, and means controlled by the longitudinal movement of the screw shaft to prevent the actuation of the motors while pressure is applied to the brake shoes.

2. In a protective device of the class de-

scribed, the combination with a locomotive having driven wheels, of electric motors to drive the wheels, brake shoes adjacent the wheels, means to press the brake shoes against the wheels comprising a screw shaft adapted to limited longitudinal movement, an electrically actuated switch adapted to interrupt the circuit of the motors, and devices actuated by the longitudinal movement of the screw shaft to control the motor switch to prevent the actuation of motors while pressure is applied to the brake shoes. 65

3. The combination of the wheels, the motor, the motor circuit, devices for opening the circuit, the manually actuated rotatable and longitudinally movable shaft, means actuated by the rotary movement of the shaft to move the shoes against the wheels, said means being adapted to transmit the reactionary force from the shoes when pressing against the wheels and thereby actuating the said devices which open the circuit. 70

4. In a protective device of the class described, the combination with an electric locomotive having driving wheels, of electric motors for driving the wheels, means to retard the rotation of the wheels, resilient means to actuate the retarding means, and means made effective by the resiliency of said actuating means to prevent the actuation of the motor during the actuation of the retarding means. 75

5. In a protective device of the class described, the combination with an electric locomotive having driving wheels, of electric motors to drive the wheels, brake shoes adjacent the wheels, resilient means to press the brake shoes against the wheels, and means made effective by the resiliency of the pressure exerting means to prevent the actuation of the motors while the brake shoes are pressed against the wheels. 80

6. In a protective device of the class described, the combination with an electric locomotive having driving wheels and an electric motor for driving the wheels, of brake shoes adapted to contact with the wheels, a shaft adapted to both rotary and bodily movement, means actuated by the rotary movement of the shaft to press the brake shoes against the wheels, and means actuated by the bodily movement of the shaft to prevent the flow of electric current in the motor. 85

7. In a protective device of the class described, the combination with an electric locomotive having driving wheels and an electric motor to drive the wheels, of brake mechanism adapted to retard the rotation of the wheels, and means actuated by the reactionary pressure of the brake mechanism to prevent the flow of current in the motor. 90

8. In a protective device of the class described, the combination with an electric

locomotive having driving wheels and an electric motor to drive the wheels, of brake shoes adapted to contact with the wheels, means to press the brake shoes against the 5 wheels, and means actuated by the reactionary pressure of the brake shoes to prevent the flow of current in the motor.

In testimony whereof I affix my signature, in the presence of two witnesses.
